DESIGN FOR A JEWELRY FINDING OR SIMILAR ARTICLE

Frank S. Moody, Los Angeles, Calif.

Application January 6, 1942, Serial No. 105,037

Term of patent 3½ years

To all whom it may concern:

Be it known that I, Frank S. Moody, a citizen of the United States, residing at Los Angeles, in the county of Los Angeles, and State of California, have invented a new, original, and ornamental Design for a Jewelry Finding or Similar Article, of which the following is a specification, reference being had to the accompanying drawing, forming part thereof.

Figure 1 is a view in front elevation of the jewelry finding or similar article embodying my new design; Fig. 2 is a top plan view of the same.

The drawing is lined to indicate color, the unlined letter P being white.

I claim:

The ornamental design for a jewelry finding or similar article, as shown and described.

FRANK S. MOODY.
